UNITED STATES PATENT OFFICE.

JOHN J. MORIARTY, OF SPRINGFIELD, OHIO, ASSIGNOR TO THE VICTOR RUBBER COMPANY, OF SPRINGFIELD, OHIO, A CORPORATION OF OHIO.

DESIGN FOR A PNEUMATIC-TIRE TREAD.

61,143.

Specification for Design. Patented June 27, 1922.

Application filed September 12, 1921. Serial No. 500,232. Term of patent 14 years.

To all whom it may concern:

Be it known that I, JOHN J. MORIARTY, a subject of the King of Great Britain, residing at Springfield, in the county of Clark and State of Ohio, have invented a new, original, and ornamental Design for Pneumatic-Tire Treads, of which the following is a specification, reference being had to the accompanying drawing, forming part thereof.

The figure is a perspective view of a portion of a pneumatic tire casing showing my new design.

I claim:

The ornamental design for a pneumatic tire tread, as shown.

JOHN J. MORIARTY.
